UNITED STATES PATENT OFFICE.

JOHN V. BUCKLE, OF SALT LAKE CITY, UTAH.

DESIGN FOR A BADGE OR SIMILAR ARTICLE.

44,913.

Specification for Design.

Patented Nov. 25, 1913.

Application filed September 19, 1913. Serial No. 790,801. Term of patent 14 years.

To all whom it may concern:

Be it known that I, JOHN V. BUCKLE, a citizen of the United States, residing at Salt Lake City, in the county of Salt Lake and State of Utah, have invented a new, original, and ornamental Design for a Badge or Similar Article, of which the following is a specification, reference being had to the accompanying drawing, forming part thereof.

The figure is a plan view of a badge or similar article, showing my improved design.

I claim:—

The ornamental design for a badge or similar article, as shown.

JOHN V. BUCKLE.
